US0D1080258S

(12) **United States Design Patent** (10) Patent No.: **US D1,080,258 S**
(45) Date of Patent: ** Jun. 24, 2025

(54) **DESK**

(71) Applicant: **ODK TECHNOLOGY PTE. LTD.,**
Singapore (SG)

(72) Inventor: **Hongbing Zheng**, Hangzhou (CN)

(73) Assignee: **ODK TECHNOLOGY PTE. LTD.,**
Singapore (SG)

(**) Term: **15 Years**

(21) Appl. No.: **29/887,391**

(22) Filed: **Mar. 21, 2023**

(30) **Foreign Application Priority Data**

Oct. 9, 2022 (CN) 202230660658.0

(51) **LOC (15) Cl.** **06-03**

(52) **U.S. Cl.**
USPC **D6/648**

(58) **Field of Classification Search**

USPC D6/329, 641, 648-648.2, 649, 652, 655,
D6/655.1, 655.11, 655.12, 655.15, 655.18,
D6/655.19, 655.22, 656, 656.16, 656.17,
D6/656.18, 656.19

CPC A47B 17/033; A47B 13/06; A47B 17/003;
A47B 17/006
